(57) **CLAIM**

We claim the ornamental design for the eccentric block device, as shown and described.

DESCRIPTION

FIG. 1 is a prospective view of the eccentric block device showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is another prospective view thereof.

The broken lines show portions of an eccentric block device which form no part of the claimed design.
